EXTREME PRESSURE SOAP AND COMPLEX THICKENED GREASES

Gerard P. Caruso, New Orleans, La., assignor to Shell Oil Company, New York, N.Y., a corporation of Delaware
No Drawing. Filed Dec. 22, 1964, Ser. No. 420,425
7 Claims. (Cl. 252—18)

This invention relates to non-clay thickened grease lubricants having improved extreme-pressure properties. More particularly, the invention relates to certain soap- and complex-thickened greases which are improved with regard to their ability to lubricate properly under extreme pressure (EP) conditions.

Prior to about 1940, nearly all grease requirements were met with uninhibited mineral oil thickened with calcium, sodium, or aluminum soaps. However, in the early 1940's the discovery of lithium soap thickened greases led to the development of water-resistant greases having high melting points and superior low-temperature properties. Later, in the 1950's, the discovery of lithium hydroxystearate-thickened greases paved the way for multi-purpose greases having excellent shear stability coupled with water resistance and good high- and low-temperature properties. In the late 1950's the need by industry and the armed forces for improved performance at temperatures ranging from —100 to +600° F. led to the development of many new types of oils, thickeners and additives.

While new thickeners, particularly waterproofed clays, have opened new vistas of grease performance, soap-thickened and complex-thickened greases still represent by far the major part of grease production and use in the world.

One of the major problems in the formulation of greases, particularly non-clay-thickened greases, is that of extreme-pressure (EP) properties, that is, the formulation of greases which have high film strength under high pressures. Literally thousands of materials of highly varying degrees of effectiveness, have been proposed to improve the EP properties of conventional greases. Among the many types of EP additives are sulfur, selenium and tellurium compounds, metal chlorides and sulfides and the like. In particular, certain metal sulfides, which are themselves good solid lubricants having EP properties, have been suggested for incorporation into grease. Among the metal sulfides which have been tried are antimony sulfide, molybdenum sulfide and zinc sulfide. However, such metal sulfides have not generally been found to be satisfactory EP agents in grease without the use of other additives to reduce the abrasiveness of such materials. For example, it is disclosed in U.S. 2,285,739 to use lead naphthenate in conjunction with zinc sulfide to reduce the abrasiveness of the metal sulfide. However, despite the extensive work on the use of metal sulfides in grease, the degree of EP effectiveness heretofore attainable in view of the cost of such lubricants, has not been sufficient to bring about their widespread application. Though, recently, waterproofed clay-thickened EP greases containing amorphous metal sulfides (antimony or molybdenum) have become available and are gaining increasingly wide acceptance, soap- or complex-thickened greases having comparable EP properties have been hitherto unobtainable.

However, applicant has now discovered that soap or complex greases having excellent EP properties can be made economically by incorporation therein of amorphous antimony trisulfide. More particularly applicant's invention is a naphthenate-free grease composition consisting essentially of (1) a lubricating base oil containing minor amounts each of (2) an oil-soluble sulfonate corresponding to the formula

2

wherein A is selected from the group consisting of alkali metal, alkaline earth metal, ammonium and omega-amino alkyl ammonium, n equals the valence of A and R is a monovalent hydrocarbyl radical selected from the group consisting of alkyl, aryl, alkaryl or aralkyl groups containing at least 6 carbon atoms, and (3) a metal sulfide primary EP agent, the lubricating oil being thickened to grease consistency by means of a soap-base thickening agent.

By the term "soap-base thickening agent," as used herein, is meant metal soaps of fatty acids which are capable of providing a stable gel structure to lubricating base oils. The term is intended to include conventional metal soaps, complex soaps, mixed base soap greases, and the like, and includes the following particular types of soap thickeners:

Metal base:

Aluminum base
Barium base
Calcium base
Lithium base
Sodium base
Lead soap base
Strontium base

Mixed bases:

Sodium-calcium base
Sodium-barium base
Calcium-aluminum base
Sodium-aluminum base
Magnesium-aluminum base
Lithium-aluminum base

Metal complex:

Hydrated calcium soap
Hydrated aluminum soap
Hydrated barium soap
Hydrated lithium soap
Hydrated sodium soap
Hydrated strontium soap
Complex aluminum soap
Complex barium soap
Aluminum-barium complex
Aluminum-sodium complex
Complex calcium soap
Calcium soap-calcium acetate complex
Calcium soap-calcium chloride complex
Calcium soap-strontium hydrate complex
Calcium-barium soap complex
Lithium soap-lithium acetate
Magnesium soap complex
Lead soap complex
Sodium soap-sodium acetate complex
Sodium soap-sodium acrylate complex
Sodium-barium complex
Strontium-calcium acetate complex

Though the lubricating base oil component of the invention can be either a natural or synthetic oil, as a practical matter, the base oil will usually be a natural oil, e.g. a petroleum-derived mineral oil. Many synthetic oils such as silicone oils and various esters can be thickened effectively with soap thickeners; however, the thermal stability of soaps is usually considerably lower than the synthetic oils. Therefore there is usually no point in using expensive synthetic oils with soap greases. Exceptions to this, however, are some of the complex greases which possess considerably higher thermal stability than the conventional soap-base greases.

The sulfonates which are useful in accordance with the invention are the salts of alkali metals or alkaline earth metals and oil-soluble monosulfonic acids. These are frequently of petroleum origin. Examples of typical suitable sulfonates are given in the following table.

TABLE I.—ANALYSES OF TYPICAL SULFONATES

	Sodium Petroleum Sulfonate	Calcium Petroleum Sulfonate	Barium Petroleum Sulfonate	Strontium Petroleum Sulfonate	Barium Naphthalene Sulfonate	Sodium Naphthalene Sulfonate	Ammonium Dinonyl Naphthalene Sulfonate	Ethylene Diamine Dinonyl Naphthalene Sulfonate

¹ Maximum.

The metals which can be used in the sulfonates are the alkali metals (Periodic Group IA) sodium and potassium and the alkaline earth metals (Periodic Group IIA), calcium, strontium and barium.

Within the context of the foregoing chemical structural formula

when A is omega-amino alkyl ammonium or alkyl ammonium, the alkyl portion thereof contains from 2 to 6 carbon atoms. A process for the preparation of sulfonates of this type is disclosed in U.S. Patent 2,764,548 issued Sept. 25, 1956. The ammonium sulfonic acid salts are prepared by reaction of the sulfonic acid with aqueous solutions of appropriate aliphatic or aryl primary, secondary or tertiary amines, e.g. dimethylamine, ethylenediamine, mono-, di- and triethyleneamine. The metal sulfides which are used as the primary EP agent in the grease composition of the invention include molybdenum disulfide, an amorphous antimony sulfide and mixtures thereof. The amorphous antimony sulfide is specified as contrasted to the crystalline antimony sulfides. The latter, normally obtained by the mining of certain minerals such as stibnite, actually causes abrasion of metallic parts. This may be due either to the extreme hardness of crystals or may be due to natural-occurring impurities such as silicates or silica present in the mineral. The amorphous antimony sulfides (e.g., antimony trisulfide, antimony tetrasulfide, or antimony pentasulfide and mixtures thereof) vary in color from yellow to gray but usually are some variety of red, dependent upon the precise means of preparation and more particularly upon the particle size of the amorphous sulfide. They are preferably obtained by precipitation of the antimony sulfide from an aqueous solution of a water-soluble antimony salt, such as antimony chloride, by treatment with a sulfide such as sodium sulfide or hydrogen sulfide.

The term "primary EP agent" is applied to the metal sulfides within the context of the invention; since, as will be shown by the following examples, the metal sulfides are substantially ineffective to improve the EP properties without the presence of the above-described sulfonates.

Example I

To a number of samples of lithium soap greases of varying composition were added small amounts of amorphous antimony trisulfide. The antimony trisulfide was thoroughly dispersed through the grease, after which each of the greases was subjected to the Timken Extreme Pressure Test (ASTM Bulletin 228, February, 1958, pages 28-31). As is shown by the following table, none of the soap greases containing amorphous antimony trisulfide exhibited any substantial increase in its load-carrying properties even at extremely high metal sulfide concentrations.

TABLE II.—EP PROPERTIES OF METAL SULFIDE-CONTAINING SOAP GREASES

¹ ASTM penetration range, 265-295.

Example II

A further series of experiments was then run in which the greases to which the antimony trisulfide was added also contained a minor amount of an alkaline earth metal sulfonate, in this case calcium petroleum sulfonate. Some of these greases, all of which are commercially available lubricants, also contain minor amounts of naphthenic acids or metal naphthenates as indicated. The data show that the metal sulfides are quite effective to improve the EP properties of the soap base greases but (1) only in the presence of the metal sulfonates and (2) only so long as the grease is free of any naphthenic acids or naphthenates.

TABLE III.—EP PROPERTIES OF SOAP BASE GREASES CONTAINING METAL SULFIDE AND SULFONATES

Formulation	E	F	G	H	I	J	K	L

¹ Soap of LiOH-H₂O and hydrogenated fatty acids. All formulations given on percent weight basis.

² Ethylene diamine dinonyl naphthalene sulfonate.

It is interesting to note from the above data (Formulation H) that even increasing the amount of metal sulfide failed to overcome the adverse effect of the presence of even a small amount of naphthenate.

The above data, Formulations K and L, indicate that the interaction of amorphous metal sulfides with sulfonates is not restricted to metal sulfonates but applies to organic salts of sulfonic acids as well. This is confirmed in the following example.

Example III

50 In this test, ethylene diamine dinonyl naphthalene sulfonate was substituted for alkaline earth metal sulfonate in a lithium hydroxide monohydrate-hydrogenated fatty acids soap-thickened grease. The Timken EP test results clearly showed the interaction between the sulfonate and 55 the amorphous metal sulfide.

TABLE IV.—EP PROPERTIES OF SOAP BASE GREASES CONTAINING METAL SULFIDE AND NON-METAL SULFONATE

Formulation	M
Soap, percent wt.	9.4
Lubricating Base Oil	88.1
Amorphous Sb ₂ S ₃	1.0
Non-metal Sulfonate	1.5
Timken EP Value, pounds:	—
Pass	55
Fail	60

65 The amounts of metal sulfide and metal sulfonates which are to be used in the soap EP greases of the invention can each be varied from about 0.5 to about 10.0%, 1 to 5% by weight of each being preferred. The ratio of sulfonates to metal sulfide does not appear to be critical.

Example IV

70 The quite unexpected interaction of the sulfonates and the amorphous metal sulfides is perhaps most graphically 75 illustrated in view of the facts (1) that the metal sulfide

has substantially no EP activity in soap greases without the sulfonates (see Table II) and yet (2) in clay-thickened greases, in which the metal sulfides have at least some EP effectiveness, the sulfonates apparently do not effectively interact with the amorphous metal sulfides. This is illustrated by the following comparative tests in which the Timken EP properties of two identical naphthenate-free clay-thickened greases containing equal amounts of Sb_2S_3 were compared with and without 3.0% by weight of calcium petroleum sulfonates. The results were as follows:

TABLE V.—EP PROPERTIES OF METAL SULFIDE-CONTAINING CLAY-THICKENED GREASES

Formulation	N	O

Timken EP Value, pounds:		
Pass	40	40
Fail	45	—

In the following table, a number of different grease formulations within the scope of the invention are exemplified.

2. The composition of claim 1 in which the mixture (3) consists of (a) calcium petroleum sulfonates and (b) amorphous antimony trisulfide.

3. The composition of claim 1 in which the mixture (3) consists of (a) sodium petroleum sulfonates and (b) amorphous antimony trisulfide.

4. The composition of claim 1 in which the mixture (3) consists of (a) omega-amino- C_{2-6} -alkyl ammonium alkaryl sulfonate and (b) amorphous antimony trisulfide.

5. The composition of claim 1 in which the mixture (3) consists of (a) ammonium alkaryl sulfonate and (b) amorphous antimony trisulfide.

6. A soap base grease composition having improved extreme pressure properties consisting essentially of (1) a lubricating base oil thickened to grease consistency with (2) a thickening amount of the lithium soap of 12-hydroxy stearic acid and (3) a mixture containing 0.5–10.0% by weight, basis total composition, each of (a) calcium petroleum sulfonates and (b) amorphous antimony trisulfide, the composition being further characterized as containing no naphthenate compounds.

7. A soap base grease composition having improved extreme pressure properties consisting essentially of (1)

TABLE VI.—SOAP BASE EP GREASES CONTAINING METAL SULFIDES AND ALKALI- OR ALKALINE EARTH-METAL SULFONATES

Lubricating Base Oil, percent wt.	Thickening Agent		Metal Sulfide		Sulfonate	
	Percent weight	Type	Percent weight	Type	Percent weight	Type

I claim as my invention:

1. A soap base grease composition having improved extreme pressure properties consisting essentially of (1) a lubricating base oil thickened to grease consistency with (2) a thickening amount of metal-containing soap, and (3) a mixture containing 0.5–10.0% by weight, basis total composition, each of (a) an oil-soluble sulfonate corresponding to the formula

wherein A is selected from the group consisting of alkali metal, alkaline earth metal, ammonium and omega-amino- C_{2-6} -alkylammonium, n equals the valence of A and R is a monovalent hydrocarbyl radical selected from the group consisting of alkyl, aryl, alkaryl and aralkyl containing at least 6 carbon atoms, and (b) a metal sulfide selected from the group consisting of an amorphous antimony sulfide and molybdenum disulfide; the composition being further characterized as containing no naphthenate compounds.

60 a lubricating base oil thickened to grease consistency with (2) a thickening amount of the lithium soap of 12-hydroxy stearic acid and (3) a mixture containing 0.5–10.0% by weight, basis total composition, each of (a) ethylenediamine dinonylnaphthalene sulfonate and (b) amorphous antimony trisulfide, the composition being further characterized as containing no naphthenate compounds.
